UNITED STATES PATENT OFFICE.

CLYDE J. COLEMAN, OF NEW YORK, N. Y.

REFRIGERATING APPARATUS.

1,014,120.

Specification of Letters Patent.

Patented Jan. 9, 1912.

Application filed June 19, 1901. Serial No. 65,116.

To all whom it may concern:

Be it known that I, CLYDE J. COLEMAN, a citizen of the United States, and a resident of the borough of Manhattan, in the county of New York, city of New York, and State of New York, have invented new and useful Improvements in Refrigerating Apparatus, of which the following is a specification, reference being had to the accompanying drawings, forming part thereof.

My invention relates to refrigerating apparatus.

My invention consists in the provision of a gaseous jet device or ejector or injector for causing the desired movement of the refrigerant medium and producing the low pressure approaching a vacuum in the cooling chamber, and further for producing compression of the refrigerant medium and the desired pressure during the condensing operation.

My invention further consists in the employment for such purpose or purposes of a multiple jet exhauster, or exhauster and compressor, wherein the jets are employed successively or in series and the ejector or injector action is compounded.

My invention further consists in the combination, with such exhauster, or exhauster and compressor, of automatic means controlled by the condition of the refrigerant medium in the cooling chamber and controlling the supply of motive medium to the exhauster, or exhauster and compressor.

My invention further consists in the combination, with the exhauster or exhauster and compressor, of a static column feed, and further of means for heating the motive medium combined with the static column feed.

My invention further consists in means for countercurrently interchanging heat from the compressed medium to the motive medium and further in means for employing the same medium as the motive medium for the exhauster and compressor and as the refrigerant medium.

My invention further consists in the provision of automatic means for insuring the liquefaction of the refrigerant medium before it enters the expansion and cooling means, and further in providing for the control by the liquefied refrigerant medium of the flow of the refrigerant medium from

the heat abstracting means or condenser to the expansion and cooling means.

My invention further consists in the employment of float actuated means for such purpose and in various improvements in the construction and combinations of parts.

I will now describe the refrigerating apparatus embodying my invention illustrated in the accompanying drawings and will thereafter point out my invention in claims.

The main parts of the apparatus shown comprise a gaseous jet exhauster and compressor 1, a condenser 2, and an expansion or cooling chamber 3. The gaseous jet exhauster and compressor in the embodiment of my invention shown comprises a plurality of ejector or injector nozzles 14, of which three are shown, arranged to operate successively or in series upon the refrigerant medium, and arranged within corresponding restricting and directing nozzles 75 for the refrigerant medium, and this gaseous jet exhauster and compressor receives its motive medium from a heating chamber or vapor boiler 4 and by its exhaustive action withdraws vaporized refrigerant medium 80 from the expansion or cooling chamber 3 through a conduit 6, and the commingled motive medium and refrigerant medium pass through the compressed medium conduit 5 and into the condenser 2. The condenser 2 is shown as a chamber having radiating ribs 16 adapted for air cooling.

The condensed medium from the condenser 2 flows into the expansion or cooling chamber 3 through the conduit 8, and means 90 are provided in such conduit for insuring the liquefaction of the refrigerant medium before it enters the expansion or cooling chamber, such means in the construction shown consisting of a float valve with a float 95 are arranged in the enlarged upper portion of the conduit 8, such enlarged upper portion constituting a float chamber 11, and a valve 10 connected thereto and located at the lower end of the conduit, where 100 it dips into the fluid in the expansion or cooling chamber. The weight of the float and to some extent the pressure in the condenser will maintain this valve closed at all times except when there is sufficient condensed fluid in the conduit to raise the float and open the valve, and this construction will effectually prevent the passage of gase-

ous refrigerant medium into the expanding or cooling chamber. Further the float chamber 11 is located outside of the expansion or cooling chamber and at a sufficient distance 5 therefrom to be located outside the refriger-
ator or space to be cooled. Further the valve 10 controlled by the float 9, is located in the expansion or cooling chamber, so that all the cooling effect of expansion takes place 10 within the expansion or cooling chamber. Further by reason of the fact that the conduit 8 dips into the fluid in the expansion or cooling chamber and that the valve 10 is immersed in the fluid in the expansion or 15 cooling chamber, the valve or expansion device is in thermal conductive adjacency and is in fact in contact with a body of the refrigerant medium capable of preventing freezing or congelation at the point of ex-
pansion.

The supply of motive medium for the gaseous jet exhauster and compressor is in the construction shown drawn from the condenser 2 and maintained by a static column feed and in this embodiment of my invention the motive medium and the refrigerant medium are the same, and the means shown are adapted for the use as the motive and refrigerant medium of water or sul- 25 feric ether or ethyl chlorid or alcohol or carbon bisulfid or other medium requiring lower pressures than ammonia.

The static column is maintained in the conduit 12, which is shown as extending at 30 its upper end from the float chamber 11 at a point below the fluid level requisite to open the condensed medium supply valve 10, so that the static column will be supplied with fluid refrigerant medium be- 35 fore any of such medium can enter the expansion and cooling chamber 3. The static column conduit enters the heating chamber or vapor boiler 4, having a return bend upwardly extending portion shown as in the form of a helical coil and this conduit in the cooler portions thereof is surrounded by a correspondingly coiled downwardly extending part of the compressed medium conduit 5, the latter conduit extending from the gaseous jet exhauster and compressor 1 to the condenser 2, and through these coiled 40 portions of the conduits the mediums are fed countercurrently and in thermal conductive proximity to each other, and the heated compressed medium flowing through the compressed fluid conduit preheats the motive medium flowing into the vapor boiler or heating chamber.

The heating means shown comprises a 45 heating chamber or vapor boiler 4, heated by a gas flame from the burner 17. The motive medium from the static column conduit 12 enters the heating chamber at its lower portion and the heating chamber is divided horizontally near the upper end

thereof by a partition 18 having an opening therethrough adapted to be closed by the valve 19, the valve 19 being carried by the pivoted float 20. The steam or vapor outlet is located above this partition, and the outlet conduit 21 leads separately into each one of the three jet nozzles 15. The function of the float and valve 20, 19, is to prevent the passage of liquefied medium to the jet nozzles, the float 20 operating to close the valve 19 before the fluid level in the heating chamber reaches the partition 18.

For the purpose of automatically controlling the heating means so as to regulate the supply of motive medium to the ex-
hauster and compressor and thereby regulate the exhausting action of the exhauster and compressor in accordance with the demands for refrigerating action in the cooling chamber, I provide a thermostat 22 shown as a bimetallic strip adjusted so as to come in contact with an electric terminal 23, and thereby close a circuit from the battery 24 through an electromagnetic valve 25 interposed in the supply pipe 26 of the burner 17, and to close such a circuit and actuate such valve when the temperature of the cooling chamber rises above that selected as affording the desired degree of refrigeration. It is of course evident that other than electrical means can be employed to effect this control. By this means the condition of the refrigerant medium in the cooling chamber 3 controls the heating means of the heating chamber 4 and thereby regulates the supply of motive medium to the exhauster and compressor. The conduit 6 from the cooling chamber 3 to the exhauster and compressor is shown as provided with a flap check valve 7 therein which closes against retrograde movement of the refrigerant medium so that when the automatic means diminishes or discontinues the action of the exhauster and compressor to such an extent that it will not exhaust the refrigerant medium through the conduit 6, the check valve 7 will close and prevent back pressure through such conduit.

It is evident that various modifications may be made in the construction above shown and above particularly described within the spirit and scope of my invention.

What I claim and desire to secure by Letters Patent is:—

1. A refrigerating apparatus comprising a cooling chamber, a conduit extending therefrom above the fluid level therein, means for generating a power medium, a gaseous jet exhauster entering the conduit and connected to the generating means so as to receive power medium therefrom, and a static column feed conduit communicating with and leading to the generating means.

2. A refrigerating apparatus comprising a cooling chamber, a condenser, a conduit

extending from the cooling chamber above the fluid level therein, means for generating a power medium, a gaseous jet exhaust entering the conduit and connected to the generating means so as to receive power medium therefrom, and a static column feed conduit communicating with and leading to the generating means.

3. A refrigerating apparatus comprising a cooling chamber, a conduit leading thereto, means for generating a power medium, a compound gaseous jet device leading from the generating means and successively arranged in the conduit, and a static column feed conduit communicating with the condenser and leading to the generating means and arranged to supply medium thereto.

4. A refrigerating apparatus comprising a cooling chamber, a condenser, a conduit extending from the cooling chamber to the condenser, means for heating a power medium, a compound gaseous jet device leading from the generating means and arranged in the conduit and a static column conduit communicating with the condenser and leading to the power medium heating means and supplying medium thereto.

5. In a refrigerating apparatus, in combination, a cooling chamber, a conduit leading thereto, a gaseous jet exhaust for expanding the medium in the cooling chamber and withdrawing the same therefrom, means for supplying motive medium to the exhaust including motive medium generating means, a static column feed conduit communicating with the condenser and leading to the generating means, and automatic means controlled by the condition of the refrigerant medium in the cooling chamber and controlling the supply of motive means to the exhaust.

6. In a refrigerating apparatus, in combination, a cooling chamber, a condenser, a gaseous jet device for expanding the medium in the cooling chamber and withdrawing the same therefrom and forcing the same into the condenser, means for supplying motive medium to the gaseous jet device, a static column feed conduit communicating with the condenser and leading to the generating means, and automatic means controlled by the condition of the refrigerant medium in the cooling chamber and controlling the supply of motive medium to the gaseous jet device.

7. In a refrigerating apparatus, in combination, a cooling chamber, a conduit leading thereto, a gaseous jet-exhaust for expanding the medium in the cooling chamber and withdrawing the same therefrom, means for generating the motive medium for the exhaust, a static column feed conduit communicating with the first conduit and leading to the generating means, and

automatic means controlled by the condition of the refrigerant medium in the cooling chamber and controlling the supply of motive medium to the exhaust.

8. In a refrigerating apparatus, in combination, a cooling chamber, a condenser, a gaseous jet exhaust and compressor for expanding the medium in the cooling chamber and withdrawing the same therefrom, and forcing the same into the condenser, means for generating the motive medium for the exhaust and compressor, a static column feed conduit communicating with the condenser and leading to the generating means, and automatic means controlled by the condition of the refrigerant medium in the cooling chamber and controlling the supply of motive medium to the exhaust and compressor.

9. In a refrigerating apparatus, in combination, a cooling chamber, a conduit leading thereto, a gaseous jet exhaust for expanding the medium in the cooling chamber and withdrawing the same therefrom, means for generating the motive medium for the exhaust, a static column feed conduit communicating with the first conduit and leading to the generating means, and automatic means controlled by the condition of the refrigerant medium in the cooling chamber and controlling the generating means.

10. In a refrigerating apparatus, in combination, a cooling chamber, a condenser, a gaseous jet exhaust and compressor for expanding the medium in the cooling chamber and withdrawing the same therefrom and forcing the same into the condenser, means for generating the motive medium for the exhaust and compressor, a static column feed conduit communicating with the condenser and leading to the generating means, and automatic means controlled by the condition of the refrigerant medium in the cooling chamber and controlling the motive power medium generating means.

11. In a refrigerating apparatus, in combination, a cooling chamber, a condenser, a gaseous jet exhaust and compressor for expanding the medium in the cooling chamber and withdrawing the same therefrom and forcing the same into the condenser, a static column conduit connected to the condenser and arranged to feed motive power generating medium therefrom to the motive power medium generating means and to the exhaust and compressor, and means for generating the motive medium in its movement from the condenser to the exhaust and compressor and controlled by the heating means.

12. In a refrigerating apparatus, in combination, a cooling chamber, a condenser, a gaseous jet exhaust and compressor for expanding the medium in the cooling chamber

- ber and withdrawing the same therefrom and forcing the same into the condenser, a static column conduit connected to the condenser and arranged to feed motive power generating medium from the condenser to the motive power medium generating means and to the exhauster and compressor, means for generating the motive medium in its movement from the condenser to the exhauster and compressor, and automatic means controlled by the condition of the refrigerant medium in the cooling chamber and controlling the motive medium generating means.
13. A refrigerating apparatus comprising a cooling chamber, a gaseous jet exhauster for expanding the medium in the cooling chamber and withdrawing the same therefrom, a conduit from the exhauster to the cooling chamber, means for generating a power medium and supplying the same to the exhauster and a medium supplying conduit from the cooling chamber to the generating means, the conduit from the exhauster and the medium supplying conduit for the generating means being arranged in thermal conductive proximity to one another and so arranged that the mediums will be conveyed countercurrently therethrough.
14. A refrigerating apparatus comprising a cooling chamber, a condenser, a conduit between the cooling chamber and the condenser, a gaseous jet exhauster and compressor for expanding the medium in the cooling chamber and withdrawing the same therefrom and forcing the same into the condenser, a conduit for the medium from the exhauster and compressor to the condenser, means for generating a power medium and supplying the same to the exhauster and compressor and a conduit from the condenser for supplying a medium to the generating means, the conduit from the exhauster and compressor and the medium supplying conduit for the generating means being arranged in thermal conductive proximity to one another so arranged that the mediums will be conveyed countercurrently therethrough.
15. A refrigerating apparatus comprising a cooling chamber, a gaseous jet exhauster and compressor, a conduit from the cooling chamber to the exhauster and compressor, a condenser, a compressed medium conduit from the exhauster and compressor to the condenser, means for generating a power medium and supplying the same to the exhauster and compressor and a medium supplying conduit from the condenser to the generating means, the compressed medium conduit and the medium supplying conduit for the generating means being arranged in thermal conductive proximity to one another so arranged that the mediums will be conveyed countercurrently therethrough.
16. In a refrigerating apparatus, in combination, a cooling chamber, a gaseous jet exhauster and compressor, a conduit from the cooling chamber to the exhauster and compressor, a condenser, a compressed medium conduit from the exhauster and compressor to the condenser, means for generating the motive medium before it enters the exhauster and compressor, a static column feed conduit from the condenser to the generating means having a return bend upwardly extending portion in proximity to the generating means, and the compressed medium conduit and the return bend portion of the feed conduit being arranged in thermal conductive proximity to one another so as to convey the mediums countercurrently therethrough.
17. In a refrigerating apparatus, in combination, a cooling chamber, a gaseous jet exhauster and compressor, a conduit from the cooling chamber to the exhauster and compressor, a condenser, a compressed medium conduit from the exhauster and compressor to the condenser, means for generating the motive medium before it enters the exhauster and compressor, and a medium feed conduit from the condenser to the generating means, the compressed medium conduit and the medium feed conduit being arranged in thermal conductive proximity to one another so as to convey the medium countercurrently therethrough, and automatic means controlled by the condition of the refrigerant medium in the cooling chamber and controlling the means for generating the motive medium.
18. In a refrigerating apparatus, in combination, a cooling chamber, a gaseous jet exhauster and compressor, a conduit from the cooling chamber to the exhauster and compressor, a condenser, a compressed medium conduit from exhauster and compressor to the condenser, means for generating the motive medium before it enters the exhauster and compressor, a static column feed conduit from the condenser to the generating means, having a return bend upwardly extending portion in proximity to the generating means, and the compressed medium conduit and the return bend portion of the feed conduit being arranged in thermal conductive proximity to one another so as to convey the mediums countercurrently therethrough, and automatic means controlled by the condition of the refrigerant medium in the cooling chamber and controlling the means for generating the motive medium.
19. A refrigerating apparatus comprising a low pressure cooling chamber, a high pressure condenser, means for expanding the refrigerant medium in the cooling chamber and withdrawing the same from the cooling chamber and compressing the refrigerant medium and forcing the same into the con-

denser, and an expansion device in the cooling chamber and automatically operable to control the flow of refrigerant medium from the high pressure condenser to the low pressure cooling chamber.

20. A refrigerating apparatus comprising a low pressure cooling chamber, a high pressure condenser, means for expanding the refrigerant medium in the cooling chamber 10 and withdrawing the same from the cooling chamber, and compressing the refrigerant medium and forcing the same into the condenser, and an expansion valve in the cooling chamber and automatically operable to 15 control the flow of refrigerant medium from the high pressure condenser to the low pressure cooling chamber.

21. In a refrigerating apparatus, in combination, means for compressing a refrigerant medium, a condenser, a cooling chamber, a conduit from the condenser to the cooling chamber having a float chamber

therein in proximity to the condenser, such conduit being constructed to dip into refrigerant fluid in the cooling chamber, a 25 float in the float chamber, and a valve in the cooling chamber controlled by the float.

22. A refrigerating apparatus comprising a cooling chamber, a condenser, a conduit leading from the condenser to the cooling 30 chamber, a gaseous jet exhauster for expanding the medium in the cooling chamber and withdrawing it therefrom and forcing motive power medium into the condenser, a heating chamber for generating 35 motive power medium and automatic means for controlling the passage of medium from the heating chamber to the exhauster.

Signed at New York, N. Y., this 13th day of June, 1901.

CLYDE J. COLEMAN.
